UNITED STATES PATENT OFFICE.

RALPH P. STINEMAN AND ONA O. TAYLOR, OF SAN DIEGO, CALIFORNIA.

MOTION-PICTURE-PROJECTOR GEARING.

1,167,854.

Specification of Letters Patent. Patented Jan. 11, 1916.

Application filed October 5, 1915. Serial No. 54,154.

To all whom it may concern:

Be it known that we, RALPH P. STINEMAN and ONA O. TAYLOR, citizens of the United States of America, residing at San Diego, in the county of San Diego and State of California, have invented certain new and useful Improvements in Motion-Picture-Projector Gearing, of which the following is a specification.

10 This invention relates to a motion picture machine and more particularly to the film actuating mechanism of this machine.

The object of the invention is to provide an improved driving means for the film of 15 a motion picture machine constructed in such manner that pictures upon the film will be presented before the lens at the usual number per minute, but will be actuated at double the usual rate of speed during the 20 time that they are moving. Consequently the length of time that is necessary to keep the shutter shut will be reduced by half, and the result will be that much of the objectionable flicker will be eliminated and the 25 amount of light required will be reduced.

Further objects and advantages of the invention will be set forth in the detailed description which now follows.

In the accompanying drawings, Figure 1 30 is a plan view of a mechanism constructed in accordance with the invention. Fig. 2 is a detailed view of a two pin Geneva movement hereinafter described, and Fig. 3 is a like view of a single pin Geneva movement.

35 Like numerals designate corresponding parts in all of the figures of the drawings.

The mechanism forming the subject matter of the present invention, may if desired, be mounted within a casing 5 so that it may 40 run in oil, but this forms no part of the invention proper. This casing forms bearings indicated in a general way at 6 supporting the several shafts hereinafter described.

45 8 designates the main driving shaft to which motion is applied through a pinion 9. This shaft carries a balance or fly wheel 10 and a disk 11 of a single pin Geneva movement. The pin of this movement is indicated at 12, and the disk 11 carries the usual segmental boss 13 which is cut out at 14 to permit the projecting members of a star wheel 15 to pass therethrough when the pin 12 engages said star wheel. The star wheel 15 is mounted upon a shaft 16 and this shaft 50 drives to a shaft 17 through the medium

of a two-to-one gearing comprising the gear 18 and pinion 19. It is apparent therefore that shaft 17 will rotate at double the rate of speed of shaft 16. Mounted upon the 60 shaft 17 is a disk 20 of a two pin Geneva movement. The pins 21 of this disk are mounted diametrically opposite each other and the disk carries curved ribs 22 which are spaced from each other to leave the cut 65 out portions 23 and 24 through which the projecting portions of the star wheel may pass when the pins 21 engage the star wheel in the usual way. Both the star wheel 25 and the star wheel 15 are provided with the 70 usual radial recesses 27 and 28 with which the pins 21 and 12 engage in the usual way. The star wheel 26 is mounted upon the shaft 27 of the film carrying sprocket wheels 29.

The elements herein described down to 75 and including star wheel 15 and shaft 16 correspond with the elements heretofore used for imparting the necessary step by step movement to the sprocket carrying shaft of a motion picture machine. However it is to be noted that the addition of the remaining elements that is those numbered 80 from 18 to 26 results in securing the objects and advantages sought. Assuming that the fly wheel 10 rotates at the rate of 85 16 revolutions per second it follows that the star wheel 15 and shaft 16 will rotate at the rate of 4 revolutions per second. The two-to-one gearing will result in rotating the shaft 17 at the rate of 8 revolutions per second and since an impulse is imparted to 90 star wheel 26 at every half revolution of disk 20 it follows that the star wheel 26 and shaft 27 together with the film carrying sprockets 28 will rotate at the rate of four 95 revolutions per second, that is they will receive just as many revolutions per second as the star wheel 15 and the shaft 16, but during the time that movement is being imparted to the film carrying sprockets they 100 are moved at double the rate of speed of star wheel 15, whereby the objects hereinbefore set forth are efficiently achieved.

While the elements shown and described are well adapted to serve the purposes for 105 which they are intended it is to be understood that many other embodiments of the inventive idea involved may be resorted to without departure from the invention.

Having described our invention what we 110 claim is:

The combination with a driving shaft and

a film carrying driven shaft of an intermediate shaft, a single pin Geneva movement between the driving shaft and said intermediate shaft a double pin Geneva movement between the film carrying shaft and said intermediate shaft and a two-to-one gearing between said intermediate shaft and the last named Geneva movement.

In testimony whereof we affix our signatures in the presence of two witnesses.

RALPH P. STINEMAN.
ONA O. TAYLOR.
